UNITED STATES PATENT OFFICE.

FRANCIS LLOYD LINDEMUTH, OF BABYLON, NEW YORK, ASSIGNOR TO NIAGARA ELECTROLYTIC IRON COMPANY, INC., A CORPORATION OF NEW YORK.

VACUUM-JACKETED METALLIC RECEPTACLE.

Application filed June 4, 1925. Serial No. 34,778.

To all whom it may concern:

Be it known that I, FRANCIS LLOYD LINDEMUTH, a citizen of the United States, residing at Babylon, in the county of Suffolk, State of New York, have invented certain new and useful Improvements in Vacuum-Jacketed Metallic Receptacles; and I do hereby declare the following to be a full, clear, and exact description of the invention, such as will enable others skilled in the art to which it appertains to make and use the same.

This invention relates to receptacles for foods and like substances having double walls and having the space between the walls evacuated to minimize the transmission of heat to or from the interior of the receptacle.

The invention is directed to the provision of an improvement in receptacles of this character having the two walls made of metal, whereby a receptacle is produced which can be made at a lower cost, which has a larger capacity for a given size and which is safer to use.

Vacuum-jacketed receptacles of this type have been made heretofore with the inner and outer walls formed of thin metal, the two walls having the form of bottles located one within the other with a space between them. The two walls are united, usually at the neck of the bottle, and the space between them is evacuated.

In the manufacture of bottles of this character, it has been the practice to apply to the inner wall of the interior bottle a coating of a vitreous enamel, this being employed because the acids in foodstuffs which might be placed in the container would be apt to attack the uncoated metal with resultant deterioration of the purity of the foodstuff and slow corrosion of the metal. Such coatings of enamel, however, are not entirely reliable, for it frequently occurs that there are pin-holes or cracks in the enamel such that the metal of the wall of the container is bared and a substance placed within the receptacle may come in contact with the metal.

It has also become a common practice to apply a plating of silver to the exterior wall of the inner bottle and the interior wall of the outer one so that the adjacent surfaces of these two walls have a mirror finish which greatly reduces the freedom of transmission

of heat through the double wall to or from the interior of the receptacle. Such silver platings are effective but they add substantially to the cost of the completed receptacle.

In accordance with the present invention, a superior and less costly receptacle is made by applying a plating of chromium to the inner wall of the inner bottle in place of the enamel coating heretofore commonly employed and by applying such a plating of chromium to the outer surface of the inner wall and to the inner surface of the outer wall in place of the platings of silver heretofore applied thereto. Such a chromium plating upon the inner surface of the inner bottle in substitution for the enamel coating, completely protects the metal wall to the extent of being entirely free from any imperfections whatever such as pin holes and cracks which would expose even a minute area of the metal of the wall for contact with the substance which is placed within the receptacle. Therefore, the possibility of acids in the substance contained within the receptacle attacking the metal of the inner bottle and the substance being deteriorated in quality thereby, is entirely removed. Also, the chromium plating upon the adjacent walls of the two bottles, that is, the walls of the vacuum jacket, presents a bright mirror finish which is as effective in preventing the transmission of heat waves through the double wall as the silver plating heretofore employed.

Such a chromium plating can be applied to the walls of the double wall receptacle readily and at low cost in accordance with processes which are now known and available, with the result that the cost of manufacturing the receptacles in accordance with this invention, rather than in accordance with the practice heretofore followed, is substantially reduced. Furthermore, the chromium plating on the inner surface of the inner bottle is of negligible thickness as distinguished from the appreciable thickness of the enamel coatings heretofore employed and considered essential, as a result of which the capacity of the receptacle is increased.

Such a chromium plating can be utilized in the manner above outlined whatever the metal employed in the two bottles which form the double walls of the receptacle. Usually these two bottles are made of thin

steel. I have found that the best results are obtained when the two bottles forming the walls of the double walled receptacle are made of electrolytic iron on which the 5 chromium plating is applied. Electrolytic iron may be worked to the appropriate shape readily and it possesses the requisite strength and it takes chromium plating very well and when so plated it presents a perfectly 10 smooth non-attackable, non-poisonous metallic surface which stands the action of acids of all food products without the least attack for an indefinite time, in contradistinction to the enameled wall, with which 15 lack of adhesion, scaling and cracking of the enamel and pin-holes therein are of frequent occurrence and as a consequence exposure of the metal of the wall to the acids of the substances placed within the receptacle. 20

A construction illustrating an embodiment of the invention is illustrated in the accompanying drawings in which Fig. 1 is a longitudinal section of a vacuum-jacketed 25 metallic receptacle and Fig. 2 is a sectional detail view on line 2—2 of Fig. 1.

In these drawings, 3 indicates the inner wall of the double walled receptacle and 4 the outer wall, these being in the form of 30 bottles mounted one within the other and connected at their upper ends 5 to form a closed space 6 between them which is completely exhausted of air. The receptacle so formed may be mounted within a casing 7 with suitable yielding spacers 8 interposed and a top 9 may be provided fitting upon the casing and extending over a cork 10.

The inner surface of the inner wall 3 40 is provided with a plating of chromium indicated at 11. Also, the outer surface of this inner wall 3 and the inner surface of the outer wall 4 are provided with platings 45 of chromium 12. These platings 12 provide upon the adjacent surfaces of the two walls of the receptacle a bright mirror finish

which aids greatly in preventing the transmission of heat through the wall to and from the interior of the receptacle. Also, the plating 11 on the inner surface of the 50 inner wall presents a smooth, sanitary surface which completely covers the wall, preventing quite fully the contact of any substance placed within the receptacle with the metal from which the wall is made and 55 therefore making that wall impervious to attack by acids contained in any such substance.

As above stated, the walls 3 and 4 may be made of any base metal, as for instance, thin steel as has heretofore been commonly employed, but the best results are attained when these walls are made of electrolytic iron. 60

I claim:

1. A vacuum-jacketed metallic receptacle having inner and outer metallic walls joined together to provide a space between them which is evacuated, the inner surface of the inner wall being plated with chromium to 70 provide thereon a smooth, sanitary coating fully protecting the metal from which the wall is made against attack of a substance contained within the receptacle.

2. A vacuum-jacketed metallic receptacle 75 having inner and outer metallic walls joined together to provide a space between them which is evacuated, the inner and outer surfaces of the inner wall and the inner surface of the outer wall being provided with 80 a plating of chromium.

3. A vacuum-jacketed metallic receptacle having inner and outer walls made of electrolytic iron and joined together to provide a space between them which is evacuated, the inner and outer surfaces of the inner wall and the inner surface of the outer wall being provided with a plating of 85 chromium.

In testimony whereof I affix my signature.

FRANCIS LLOYD LINDEMUTH.
